ROTATABLE BOTTLENECK CLEANING DEVICE

James F. Banks, Alexandria, Va.

Application December 26, 1947, Serial No. 793,957

2 Claims. (Cl. 15—164)

1

This invention relates to bottle cleaners, and more particularly to an improved brush for cleaning the neck of the bottles.

It is an object of this invention to provide an improved bottle neck and bead cleaner of the kind to be more particularly described hereinafter, having opposed brushes carried by a rotatting supporting member in such a manner that the increase of force on the bottle axially of the brush supporting member will increase the frictional engagement of the brush against the neck of the bottle.

Another object of this invention is to provide an improved bottle brush of this kind, having rockably supported opposed brushes carried by a brush supporting member and a sliding sleeve engaging the brush supporting parts in such a manner that movement of the sleeve will effect rocking of the brushes relative to the neck of the bottle.

A further object of this invention is to provide an improved bottle neck cleaning brush having stiff, or preferably wire, bristles for scraping the rust from the neck and bead of the bottle, and having means for selectively varying the frictional contact of the brush with the bottle.

With the above and other objects in view, my invention consists in the arrangement, combination and details of construction disclosed in the drawings and specification, and then more particularly pointed out in the appended claims.

Referring to the drawing—

Figure 1 is a top plan view of a bottle cleaning brush constructed according to an embodiment of this invention.

Figure 2 is a vertical section taken on the line 2—2 of Figure 1.

Figure 3 is a side elevation of a brush and its support, removed from the assembly.

Referring to the drawing, the numeral 10 designates generally a brush for cleaning the neck and bead of bottles or the like. The brush 10 is primarily designed for attachment to a power member 11 which may be a part of a conventional bottle washing machine, or may be an independent source of power.

In the use of bottles designated by the numeral 12, having metal caps engaging over a bead as 14 at the end of the neck, the extended use of such caps results in a deposit of rust about the bead. With conventional bottle washing devices the rust adheres closely to the bead so that it is not removed, and special, extra efforts must be used to remove this rust. The brush of this invention is formed with wire bristles designated

2

by the numeral 15, to brush and scrape the rust from the beads.

The bottle neck washing brush 10 is formed of an elongated rod or shaft 16 threaded at one end as 17 for attachment to the power member 11. The member 16 is fixed to the member 11 in such a manner that the rotation of the power member 11 will effect the rotation of the shaft 16, carrying the brushes.

10 The shaft 16 is formed at its lower end with a reduced diameter section 18, providing shoulders 19 and 20 at the extreme ends of a recess 21 formed between the diameter of the shaft 16 and the reduced section 18. A sleeve 22 is slidably and rotatably supported on this lower end of the shaft 16.

15 A bolt or pin 24 is threadably engaged through one wall of the sleeve 22 and the inner end of the bolt terminates within the recess 21 and is 20 adapted to engage the shoulders 19 and 20 on sliding movement of the sleeve for limiting this movement. With this connection the sleeve 22 is free to rotate about the shaft 16 as the shaft is driven by the power member 11.

25 A bearing sleeve or washer 25 is rotatably supported on the shaft 16 above the sleeve 22 for reasons described hereinafter. The lower end of the sleeve 22 is closed by a wall 26, having a central opening 27 therein. A reduced diameter stud or lug 28 is carried by the lower end wall 30 of the sleeve 22 and extends downwardly from the shaft 16, concentric thereto. The opening 27 is continued downward from the end wall 26 through the stud 28.

35 A rubber ring 29 of a substantially frustroconical formation is fixedly carried by the stud 28. The lower end of the sleeve 22 and the rubber seal 29 are adapted to be engaged within the end of the neck of a bottle 12 in the use of the cleaning device 10.

40 A pair of levers 30 and 31 of substantially L-shape formation are rockably carried by the shaft 16 on the opposite sides thereof. The levers 30 and 31 are formed with a substantially horizontal arm as 32 which extends radially out from the shaft 16 and an arm 34 which extends from the outer end of the arms 32 substantially parallel to the axis of the shaft 16 and at right angles to the arms 32.

45 A socket as 35 is formed on the lower end of the arms 34 for supporting therein the bristles 15 of the brush carried by the levers 30 and 31. The sockets 35 open inwardly relative to the shaft 16 in a substantially confronting relation on opposite sides of the axis of the rod 16. The free

end of the arms 32 of the levers 30 and 31 are disposed closely adjacent the surface of the shaft 16 above the sleeve 22.

The bearing 25, loose on the shaft 16, is adapted to engage the terminal ends of the arms 32 for rocking the levers about their pivot point. The levers 30 and 31 are rockably supported on opposite sides of the shaft 16 by pivot pins 36. A sleeve as 37 is fixed on the shaft 16 above the sleeve 22 thereon. A pair of outwardly and downwardly extending radially disposed arms as 38 are fixedly carried by the sleeve 37 on opposite sides of the shaft 16. The arms 38 are bifurcated for receiving therebetween the arm 32 of the levers 30 and 31. The pivot pin 36 is fixed between each of the arms 38 engaging through the arm 32 for rockably supporting the levers on the shaft 16.

In the use and operation of this bottle washing device, the brushes carried by the levers 30 and 31 are normally disposed in a divergent relation relative to each other and to the shaft 16. The centrifugal force of the levers on the rotating shaft causes the arms 34 to rock outwardly on the pivots 36 on the inner end of the levers and presses the sleeve 22 downwardly relative to the shaft 16, permitting the bearing 25 to be dropped downwardly from the arms 32, thereby permitting the rocking movement of the levers about the pivots 36 for disposing the brushes in outwardly disposed relation to each other.

The bead 14 of a bottle may be readily cleaned with this device by pressing the neck of the bottle upwardly onto the rubber pad 29 which is disposed then within the neck and will engage the upper edge thereof. Further movement of the bottle along the axis of the shaft 16 will then slide the sleeve 22 upwardly and the bearing 25 will engage the inner ends of the arms 32 for rocking the levers 30 and 31 about the pivots 36 for rocking the brushes and bristles 15 inwardly for engagement of the bristles with the outer surface of the beads 14 and neck of the bottle 12.

As the shaft 16 is continually rotated during this operation, the opposed confronting brushes will be rotated about the neck of the bottle for removing the rust and other dirt therefrom.

I do not mean to confine myself to the exact details of construction herein disclosed, but claim all variations falling within the purview of the appended claims.

What I claim is:

1. An improved bottle neck cleaning device comprising an elongated cylindrical supporting rod, said rod formed with an annular reduced diameter portion as a recess disposed adjacent one end thereof, a sleeve rotatably and slidably mounted over said one end, a pin carried by said sleeve engaging said reduced diameter portion for limiting the sliding of said sleeve on said rod,

an annular bearing carried by the top end of said sleeve, a pair of radially disposed substantially right angular rock levers, each of said levers including an arm disposed radially of said rod and an arm substantially parallel to said rod, means on said rod pivotally supporting said levers intermediate the lengths of their radial arms adjacent said one end of said rod, confronting brushes on the free ends of said parallel arms, said bearing engageable with the free ends of said radial arms in certain positions thereof along the length of said rod, and a truncated bottle engaging member of the lower end of said sleeve engageable within the neck of a bottle, whereby said brushes will be pressed into engagement with the outer surface of the neck of the bottle upon sliding of said sleeve on said rod.

2. An improved bottle neck cleaning device comprising an elongated cylindrical supporting rod having a reduced diameter portion adjacent one end thereof to provide an annular recess, a sleeve slidably and rotatably mounted over said one end of said rod, a pin extending through the side wall of said sleeve and engaging within said recess for limiting the sliding of said sleeve relative to said rod, an annular bearing member on the upper end of said sleeve and disposed about said rod, a tapered lug extending from the other end of said sleeve, a resilient cushion member disposed about said lug and engageable within the neck of a bottle, a second sleeve fixed on said rod intermediate the length thereof, diametrically opposed radially extending slotted arms formed on said second sleeve, a substantially right angular rock lever pivotally mounted intermediate the length of one leg thereof on each of said slotted arms, the other legs of said rock levers terminating adjacent to said resilient cushion member, the inner ends of said one leg of said rock levers being adapted to engage said bearing member to be rocked upwardly upon sliding of said one end of said rod inwardly with respect to said first mentioned sleeve, and inwardly directed brushes carried by said other legs at the free ends thereof for cleaning engagement with the neck of a bottle when said rock levers are rocked upwardly.
